UNITED STATES PATENT OFFICE

2,269,157

AUTOMATIC FLUID FUEL BURNER CONTROL

Samuel J. Levine, Verona, N. J., assignor to
General Electric Company, a corporation of
New York

Application July 31, 1940, Serial No. 348,949

5 Claims. (Cl. 158—117.1)

This invention relates to a control system for a fluid fuel burner of the type having a main burner and a normally out pilot burner for igniting the main burner, an igniter, motor-operated valves for controlling the main burner and pilot burner, and a relay switching system for controlling the operation of the main burner and pilot burner valve motors. In this type of control system it is common to provide a combustion responsive device associated with the pilot burner which operates a control device to prevent the energization of the main burner valve until combustion occurs at the pilot burner. This is accomplished by connecting the control device to energize the pilot burner in the "start" position and the main burner in the "run" position. This prevents the possibility of a large quantity of unburned fuel from escaping from the main burner and the resultant danger of explosion in case the pilot burner should fail to ignite for some reason during the starting operation of the burner. It has been found, however, that these combustion responsive devices do not give complete protection upon the occurrence of certain abnormal conditions. For example, assume that the burner is running normally and the main burner is energized. The fuel pressure may then dip sufficiently to put out the pilot and main burner and then immediately return to normal. Due to the fact that the combustion responsive devices often used, such as one of the thermal type, require a considerable time to return to the "start" position upon a cessation of combustion, a large quantity of unburned fuel may escape before the main burner is deenergized.

Likewise, in systems using electrically operated motors to open the control valves, a sudden dip in supply voltage during operation of the main burner may cause the valves to drop closed for a sufficient time to put out the pilot and main burner but then immediately open them upon a return of the voltage to normal. Here again a large quantity of unburned fuel may escape from the main burner before the combustion responsive device can return to the "start" position and deenergize the main burner. Also, in control circuits where the valve motors are energized through a circuit including a control switch such as a thermostat, a manual manipulation of the thermostat has the same effect on the system as a voltage dip described above.

It is an object of my invention to provide an automatic control system for a fluid fuel burner which will automatically control the operation of the pilot burner and main burner in response to

a call for heat by a control device and to embody into such a system safety control features which will give more complete protection against the escape of large quantities of unburned fuel and the resultant danger of explosion upon the occurrence of abnormal operating conditions.

More specifically, it is an object of my invention to provide a control system for a fluid fuel burner adapted to prevent the escape of unburned fuel from the main burner in the event of pilot gas failure, pilot flame failure, or igniter failure caused by abnormal operating conditions including momentary dips in fuel pressure and electrical supply voltage.

15 It is a further object of my invention to provide a control system of the type described which will be positive in operation, give a maximum of protection and which will be cheap to manufacture and install.

20 Further objects and advantages of my invention will become apparent as the following description proceeds, and the features of novelty which characterize my invention will be pointed out with particularity in the claims annexed to and forming a part of this specification.

25 My invention will be better understood from the following description taken in connection with the accompanying drawing, in which the single figure illustrates, in schematic form, one embodiment of my invention.

30 Referring now to the drawing, the main burner 10 of a fluid fuel burner, illustrated only schematically, is supplied with fluid fuel through a conduit 11 connected to the inlet conduit 12 which is connected to any suitable source of fluid fuel not shown. The conduit 11 is provided with a normally closed valve 13 operated by any suitable electrical actuating means such as a solenoid motor 14. The pilot burner 15 is supplied with fuel 35 through a conduit 16 which is connected with the fuel supply conduit 12. The pilot burner conduit 16 is likewise provided with a normally closed valve 17 operated by a suitable electrical actuating means such as a solenoid motor 18.

35 The pilot burner is of the normally out type, that is, the pilot burner is on only when the burner is in operation. This arrangement of the pilot burner is desirable because of the saving in fuel cost but some means must be provided

40 for lighting pilot burner when the burner is started. To accomplish this I have provided an electric igniter 19 of the hot wire type the connections of which will be described below. It is obvious that other well-known types of electric igniters, a platinum sponge, or a constantly burn-

ing small flame pilot, may be used to accomplish the same purpose.

When the burner is started in response to a call for heat by a suitable control device such as a thermostat 20, the pilot burner valve 17 is opened and the pilot burner lighted by the igniter 19. Subsequently, the main burner valve 13 is opened and the main burner 10 is ignited from the pilot 15.

To accomplish automatic operation of the pilot burner, main burner and igniter, I have provided switching means indicated generally at 21 controlled by any suitable combustion responsive device 22. I have shown at 22 a combustion responsive device of the thermal type comprising a thermostatic bulb 23, located adjacent the pilot burner 15, connected to a Sylphon bellows 24 by a tube 25. The bulb 23 is located so that it is not appreciably affected by the heat generated by the igniter 19. The Sylphon bellows operates the switching means 21 through a member 26. Any other suitable form of combustion responsive device might be used to operate the switching means 21.

The valve motors 14 and 18 and the igniter 19 are supplied with electrical energy from the secondary winding 30 of the transformer 28 having its primary winding 29 connected to a suitable source 27. The motors 14, 18, and igniter 19 are controlled by switching means the action of which will now be described.

In the drawing the control apparatus is shown in the "off" position. When the control switch 20 is closed such as by the movement of the bimetal member 33 of a thermostat to the left closing contacts 31, 32 in response to a call for heat in a zone heated by the burner, the pilot valve motor and igniter are energized through the switching means 21. The circuit to the pilot valve motor may be traced from the secondary 30 of the transformer 28 through line 34, thermostat 20, line 36, contact 37-a, bridging member 37, contact 37-b, line 40, pilot valve motor 18, line 35 back to secondary 30. The circuit to the igniter may be traced from secondary 30 to contact 37-b as described above, line 41, contact 38-b, bridging member 38, contact 38-a, line 42, igniter 19, line 35 back to secondary 30. The pilot valve motor being energized the valve 17 is opened and fuel is discharged from the pilot burner 15 and lighted by the energized igniter 19.

It will be noted that I have provided a holding circuit around contacts 37-a, 37-b, controlled by a switch 43. The switch 43 is actuated in response to a predetermined fuel pressure in the pilot burner conduit 16. To accomplish this I have illustrated the switch 43 connected by a member 45 to a diaphragm 44 movable in response to the pressure in chamber 46. The chamber 46 is connected to conduit 16 through a tube 47. When pilot valve 17 opens, the pressure in conduit 16, and consequently chamber 46, increases forcing diaphragm 44 upwardly thereby closing switch 43. The switch 43, when closed, shorts out the current path through bridging member 37 of switch 21. The switch is arranged to open when the fuel pressure in conduit decreases to a value slightly greater than that required to maintain combustion at the pilot burner. Thus the switch 43 will open the electrical circuit before the pressure in conduit 16 is reduced to a point where the pilot will go out or is so reduced in size that it will not ignite the fuel issuing from the main burner.

After combustion starts at the pilot burner 15

the fluid in thermostatic bulb 23 becomes heated and expands causing the Sylphon bellows to move upwardly thereby causing the bridging members 37, 38, and 39 of switch 21 to move to the "run" position indicated by the dotted lines. The opening of the contacts 37-a, 37-b has no effect on the control circuit since the energizing current passes through the holding circuit closed by switch 43. However, the opening of contacts 38-a, 38-b breaks the circuit to the igniter thereby deenergizing the same. The closing of contacts 39-a, 39-b, by the bridging member 39 completes the circuit to energize the main burner valve motor 14 thereby causing the opening of the valve and a flow of fuel to the main burner which is then ignited by the pilot burner. The circuit to the main valve motor 14 may then be traced from the transformer secondary 30 through line 34, thermostat 20, line 36, switch 43, lines 40 and 41, contact 39-b, bridging member 39, contact 39-a, line 47, solenoid motor 14 and line 35 back to transformer secondary 30.

When the thermostat 20 is satisfied the contacts 31, 32 open deenergizing the pilot burner and main burner valve motors 18 and 14 and allowing the valves 17 and 13 to close thus turning off the burners. The closing of the pilot burner valve 17 causes an immediate decrease of the pressure in conduit 16 and hence pressure chamber 46 thereby causing switch 43 to open. Subsequently the thermostatic bulb 23 cools down and gradually the Sylphon bellows contracts causing the bridging members 37, 38, and 39 of switch 21 to return to the "start" position. The control apparatus is then ready for another cycle of operation.

The operation of my control system may be summarized as follows:

Upon the closing of the control switch or thermostat 20 the pilot valve 17 is opened its motor 18 being energized through switch member 37. The igniter 19 is also heated being energized through switch members 37 and 38. As soon as pilot valve 17 opens, switch 43 closes since the gas pressure builds up a chamber 46. When the igniter reaches sufficient temperature, the pilot gas ignites and heats up the thermostatic bulb 23 causing the bellows 24 to expand opening switch members 37 and 38 and closing 39. Thus the igniter is deenergized and the motor 14 is energized opening the main burner valve. Fuel entering the main burner is then ignited by the pilot burner.

When the control switch or thermostat 20 opens, it deenergizes motors 18 and 14 closing valves 17 and 13 which turn off the gas supply to both the main and pilot burners. Pressure switch 43 then opens due to the drop of fuel pressure in conduit 16 and finally when the thermostatic bulb 23 has cooled sufficiently, switch members 37 and 38 close and 39 opens. This completes a cycle of operation.

Because of the time required for the combustion responsive device 22 to operate it is necessary to protect against abnormal conditions of operation such as voltage and fuel pressure dips which may be of short duration but sufficient to put the pilot out. Thus if no protection were provided, a voltage or fuel pressure dip might put out the pilot and main burner and then, upon a return to normal, large quantities of unburned fuel would escape from the main burner until combustion responsive device 22 could return to the "start" position and energize the igniter. The ignition then of a large quantity

of unburned fuel would likely cause a dangerous explosion.

In my control system the pressure operated switch 43 obviates this possibility. It will be noted that during main burner operation the power supply circuit to both valve control motors is completed through the pressure switch 43 since the switch member 37 is then open. A voltage dip which causes the pilot valve 17 to close, because of deenergization of its control motor 18, will drop the gas pressure in conduit 16 sufficiently to open pressure switch 43. Return of voltage to normal cannot then re-open the pilot or main valve until the combustion responsive device 22 returns to the "start" position and closes switch member 37 to recycle the operation of the control system. Manual operation of the switch 20, which produces the effect of a voltage dip is also protected against in a similar manner.

Likewise a pressure dip of sufficient magnitude to put out the pilot will open pressure switch 43. This will result in closure of the main and pilot burner valves and upon a rise in pressure of the fuel no unburned gas can escape until the recycling operation is completed. Thus the provision of a single operating means, namely, the pressure operated switch 43, operates to give protection against both supply voltage and fuel pressure failure.

Also it is evident if during the starting operation the pilot fails to ignite for some reason such as igniter failure, pilot fuel failure, etc., the combustion responsive device 22 will remain in the "start" position and the main burner valve cannot be opened to emit any dangerous quantity of unburned fuel. It is true that in case of igniter failure the pilot valve 17 will remain open upon a closure of control switch 20 but the amount of unburned fuel escaping from the pilot is so small that no dangerous condition is likely to result.

While I have shown and described a specific embodiment of my invention, it will become apparent to those skilled in the art that my invention has other applications, and that changes and modifications may be made without departing from the spirit and scope of my invention. I therefore aim in the appended claims to cover all such modifications and changes.

What I claim as new and desire to secure by Letters Patent of the United States, is:

1. In a fluid fuel burner control system, a main burner connected to a fuel supply source by a main burner conduit, a normally closed valve interposed in said main burner conduit, a pilot burner connected to said fuel supply source by a pilot conduit, a normally closed pilot valve interposed in said pilot conduit, electrically actuated opening means for the burner valve, electrically actuated opening means for the pilot valve, means for igniting the pilot burner, an energizing circuit for the main valve and pilot valve opening means, a first switch in said energizing circuit, a second switch for controlling the energization of said main valve opening means, heat responsive means associated with said pilot burner for controlling said first and second switches, said heat responsive means being normally at a "start" position in which said first switch is closed and said second switch is open and moving to a "run" position in which said first switch is open and said second switch is closed in response to combustion at the pilot burner, a holding circuit shunting said first

switch, said holding circuit including a normally open pressure switch and means for closing said pressure switch upon the attainment of a predetermined fuel supply pressure in the pilot conduit between the pilot valve and the pilot burner whereby upon a falling of said pressure below said predetermined value when said heat responsive means is in the "run" position and said first switch is open, said pressure switch opens 10 causing a deenergization of the main and pilot valve opening means and a closure of the main and pilot valves so that said pressure switch cannot reclose until said heat responsive means returns to the "start" position to close said first switch and reopen said pilot valve.

2. In a fluid fuel burner control system, a main burner connected to a fuel supply source by a main burner conduit, a normally closed valve interposed in said main burner conduit, a pilot 20 burner connected to said fuel supply source by a pilot conduit, a normally closed pilot valve interposed in said pilot conduit, electrically actuated opening means for the burner valve, electrically actuated opening means for the pilot 25 valve, means for igniting said pilot burner, a switching device having a set of normally open and a set of normally closed contacts, means dependent on the occurrence of combustion at said pilot burner for actuating said switching 30 device to close normally open contacts and to open normally closed contacts, a normally open pressure switch, means for closing said pressure switch upon attainment of a predetermined pressure in the pilot conduit between 35 said pilot valve and said pilot burner, an energizing circuit to which said pilot valve opening means is connected, said energizing circuit having a portion comprising two parallel paths, one of said paths including the normally closed contacts of said switching device and the other of 40 said paths including said pressure switch, said main burner opening means being connected in parallel with said pilot burner actuating means by a circuit including the normally open contacts of said switching device.

3. In a fluid fuel burner control system, a main burner connected to a fuel supply source by a main burner conduit, a normally closed valve interposed in said main burner conduit, a pilot 50 burner connected to said fuel supply source by a pilot conduit, a normally closed pilot valve interposed in said pilot conduit, electrically actuated opening means for the burner valve, electrically actuated opening means for the pilot 55 valve, an electrically operated igniter for said pilot burner, a switching device having a set of normally open contacts and a first and second set of normally closed contacts, means dependent upon the occurrence of combustion at the 60 pilot burner for actuating said switching device to close said normally open contacts and to open said first and second normally closed contacts, a normally open pressure switch, means for closing said pressure switch on the attainment of a predetermined pressure in the pilot conduit between the pilot valve and the pilot burner, an energizing circuit to which said pilot valve opening means is connected, said energizing circuit having a portion comprising two parallel paths, 65 one of said paths including the first normally closed contacts of said switching device and the other of said paths including said pressure switch, said main burner opening means being connected in parallel with said pilot burner opening means by a circuit including the normally open contacts of said switching device.

tacts of said switching device and said electrically operated igniter being connected in parallel with said pilot burner opening means by a circuit including the second normally closed contacts of said switching device.

4. In a fluid fuel burner control system, a fuel burner, a conduit interconnecting said burner and a source of fuel supply, a normally closed valve interposed in said conduit, electrically actuated means for opening said valve, an energizing circuit for said valve actuating means, a first switch in said energizing circuit, a holding circuit shunting said first switch, said holding circuit including a second switch, means for operating said second switch in accordance with the fuel pressure in the conduit between said valve and said burner, igniting means for said burner, and means responsive to combustion at said

burner for controlling said igniting means and said first switch.

5. In a fluid fuel burner control system, a fuel burner, a conduit interconnecting said burner and a source of fuel supply, a normally closed valve interposed in said conduit, electrically actuated means for opening said valve, an energizing circuit for said valve actuating means, a first switch in said energizing circuit, a holding circuit shunting said first switch, said holding circuit including a second switch, means for operating said second switch in accordance with the fuel pressure in the conduit between said valve and said burner, and means responsive to combustion at said burner for controlling said first switch.

SAMUEL J. LEVINE.
